Claims priority, application Germany Jan. 9, 1958
21 Claims. (Cl. 32—26)

This invention relates to handpieces for dental purposes.

In known handpieces for dental purposes which are driven by an air turbine, the air turbine is arranged at the rear end of the handpiece. This means that the driving shaft, which rotates at a high speed, extends through the entire handpiece as far as the nose of the handpiece, possibly with the interposition of a coupling. With the very high speeds of about 50,000 to 300,000 revolutions per minute, it is unavoidable that vibrations occur which not only result in loud undesirable noises but also make satisfactory support of the shaft extremely difficult.

In order to avoid these disadvantages, according to the invention it is proposed to arrange the air turbine interchangeably in the vicinity of the nose part of the handpiece jointly with the ball bearings for the turbine rotor.

It is particularly expedient for the turbine to be inserted interchangeably in the rear end of the removable nose part.

According to the invention the air turbine can also be arranged in the vicinity of the nose part in the case of a handpiece which is not divided in the longitudinal and transverse senses. In this case, the turbine is interchangeably inserted into the handpiece from the rear end thereof.

Also, according to the invention, in a handpiece with a removable nose part, the turbine can be so inserted in the front end of the handle that it can be removed in the forward direction once the nose part of the handpiece has been removed.

The arrangement of the air turbine in the vicinity of the nose part of the handpiece necessitates a driving shaft of only short length; therefore, vibration can be almost completely eliminated at this shaft. The handpieces constructed according to the invention can run substantially more quietly and can also be provided with more satisfactory bearings despite the high rotational speeds involved.

It is expedient for the air turbine to be constructed as an axial-admission turbine since, if the turbine is constructed in this way it is possible, despite the arrangement of the said turbine in the vicinity of the nose part of the handpiece, for the dimensions to be kept approximately the same as the conventional dimensions of dental handpieces.

For a better understanding of the invention and to show how it may be carried into effect, several forms of embodiment thereof will now be described, by way of example, with reference to the accompanying drawings, in which:

FIGURE 1 is a longitudinal sectional view of a handpiece wherein the turbine is interchangeably inserted in the rear end of a removable nose part.

FIGURE 2 is a diagrammatic side view of the turbine rotor with front and rear annular discs.

FIGURE 3 is a rear view of the front annular disc or a front view of the rear annular disc.

FIGURE 4 is a cross-sectional view of the handpiece taken on the line IV—IV of FIGURE 1.

FIGURE 5 is a cross-sectional view of the handpiece taken on the line V—V of FIGURE 1.

2

FIGURE 6 is a longitudinal sectional view of a modified form of embodiment of a handpiece which is not divided either in the longitudinal or transverse senses, but is provided with a turbine inserted interchangeably from the rear end of the handpiece up to the vicinity of the nose part thereof, the cross-sections on lines IV—IV and V—V of FIGURE 6 corresponding to FIGURES 4 and 5, respectively.

FIGURE 7 is a longitudinal sectional view of a further form of embodiment of a handpiece wherein the turbine is so arranged in the front end of the handle tube that the turbine can be removed in the forward direction after the nose part of the handpiece has been removed.

FIGURE 8 is a cross-sectional view of the handpiece taken on the line VIII—VIII of FIGURE 7, and

FIGURE 9 is a cross-sectional view of a handpiece taken on the line IX—IX of FIGURE 7.

The form of embodiment according to FIGURES 1 to 5, comprises a handpiece having a handle tube 1 into the front end of which a nose part 2 of the handpiece is screwed at 3. Two ball bearings 5, 6 are arranged in the front portion of the nose part at a specific distance from one another which is determined by a spacer sleeve 4. The inner races of these ball bearings are fitted onto the turbine shaft 7. The turbine shaft has a thickened or enlarged diameter rear end portion which carries a turbine rotor 8 the outer periphery of which is provided, as shown in FIGURE 2, with curved blades 9 extending in the axial direction. The turbine rotor 8 is surrounded by a turbine casing 10.

A front closure cap 11 is inserted in the front end of the turbine casing 10 and a rear closure cap 12 is inserted in the rear end of the casing. Situated within and centered by the front closure cap 11 is an annular disc 13

35 which is provided at its outer periphery with a plurality of air ducts 14 which extend obliquely to the axis of the turbine. Arranged within the rear closure cap 12 and centred thereby is a rear annular disc 15 which in its turn is also provided at its outer periphery with a plurality of ducts 16 arranged obliquely to the axis of the turbine.

The front and rear closure caps are secured against axial displacement in the turbine casing by flanging-over of the free ends of the turbine casing at 17. The front closure cap 11 of the turbine casing extends as far as the rear end of the outer race of the ball bearing 6. Situated between the outer wall of the turbine casing 10 and the inner wall of the handpiece nose part 2 is a free annular space 18 which is used for returning the turbine discharge air, as will be described hereinafter.

50 A sleeve 19 is screwed into the rear annular disc 15. Situated between a collar 20 at the rear end of the sleeve 19 and the free rear end of the rear closure cap 12 there is arranged a ring 21 which is provided with a plurality of axial holes 22 distributed about its periphery. The ring 21 is used for centering the sleeve 19 with respect to the inner wall of the handpiece nose part 2. Bearing in

55 fluid-tight manner against an internal cone at the rear end of the sleeve 19, is an air supply pipe 23 which is arranged centrally within the handle tube 1 of the handpiece. The air supply pipe has a thickened or enlarged diameter rear end portion 24 provided with a lateral stub pipe 26 to which an air supply hose can be connected.

60 The air supplied through this stub pipe 26 passes through the air supply pipe 23 into the cavity 27 in the sleeve 19 and through radial holes 28 in the wall of the sleeve, through the oblique ducts 16 in the rear annular disc 15, into the turbine rotor 8. The air discharged from the turbine flows out through the oblique ducts 14 in the front annular disc 13 and then through the radial holes 29 in the front closure cap 11, through the annular space 18 between the handpiece nose part and the turbine cas-

65

70

ing and through the axial holes 22 of the ring 21 into an annular space 30 between the handle tube 1 and the air supply pipe 23. Then, from the annular space 30, the air passes out through axial holes 31 (see also FIGURE 5) in the rear thickened end portion 24 of the air supply pipe 23, into the atmosphere.

Some of the turbine discharge air after flowing through the oblique ducts 14 in the front annular disc 13 and after passing through the ball bearings 5 and 6, reaches the tool of the instrument through nozzles 32 which are arranged in a circle about the periphery of the front end of the nose part.

A self-locking chuck 33 for the tool shank (not shown) is inserted in the front hollow end of the turbine shaft 7. This chuck 33 is formed of elastic material. The rear end of the chuck is provided with slots 34. The tongues situated between the slots 34 are curved slightly inwards. When the tool shank is inserted in the collet, the elastic tongues are pressed outwardly, and the tool shank is held fast by the elastic effect produced thereby.

Provided within the air supply pipe 23 for the purpose of removing the tool shank from the chuck 33, is a push rod 35 whose rear thickened end 36, projecting from the rear end of the handpiece, is held in a rear or retracted position by means of a spring 37 which surrounds the rear end of the push rod 35. The front end of the spring 37 bears against the end 38 of a sleeve 39 whose thickened rear end 40 is screwed at 41 into the rear thickened end 24 of the air supply pipe 23. The rear or retracted position of the push rod 35 is defined by an abutment disc 42 which bears on the end 38 of the sleeve 39. The front end of the push rod 35 is centered in a bore of the sleeve 19, and, when the push rod is not being operated, terminates approximately at the forward end face of the sleeve 19. A further push rod 43 is mounted for axial movement elastically in front of the push rod 35 within the hollow turbine shaft 7. The rear thickened end 44 of this further push rod is urged by a spring 45 against a ring 46 which is inserted fixedly in the rear hollow end of the turbine shaft 7. The front end of the second push rod 43 is guided in a bore in the turbine shaft 7 and extends approximately as far as the rear end of the tool shank (not shown) which is inserted in the chuck 33. For ejecting the tool from the chuck 33, it is merely necessary for the push rod 35 to be pushed forwards by pressure on the rear end of its thickened end portion 36 in opposition to the action of the spring 37. Then the front end of the push rod 35 presses on the thickened rear end 44 of the push rod 43 and the tool shank is pushed out of the chuck by the front end of the push rod 43. The two push rods 35 and 43 return to their initial positions as a result of the action of the springs 37 and 45.

The form of embodiment according to FIGURE 6 corresponds to a considerable extent to the form of embodiment according to FIGURES 1 to 5. Like parts are designated with reference numerals.

This form of embodiment differs from the form of embodiment according to FIGURES 1 to 5 in that the nose part 2 of the handpiece is not arranged to be detachable from the front end of the handle tube 1. In this form of embodiment, the air supply pipe 23 extends right up to a short distance from the rear end of the turbine shaft 7. The rear annular disc 15 is screwed on to the front end of the air supply pipe 23. Arranged between the rear end of the rear closure cap 12 and a collar of the air supply pipe 23 is the annular disc 21 which is also provided with axial holes 22. Otherwise the construction of the handpiece shown in FIGURE 6 corresponds to the form of embodiment according to FIGURES 1 to 5.

When the rear thickened end 24 of the air supply pipe 23 is screwed off, the air turbine with turbine shaft 7 and ball bearings 5 and 6 can be pulled out rearwardly from the handle tube together with the air supply pipe 23. Then the ball bearings 5 and 6 can be removed in the

forward direction from the turbine shaft 7 and if necessary replaced by new bearings.

In the form of embodiment according to FIGURES 7 to 9, 47 is the handle tube and 48 is the handpiece nose part which is screwed removably into the front end of the handle tube 47. The air turbine is inserted in the front end of the handle tube 47. The turbine rotor 50, which in accordance with FIGURE 2 is provided at its outer periphery with curved blades 51 (FIGURE 8) sits on the turbine shaft 52 which extends up to the front end of the nose part 48 of the handpiece. The turbine casing 53 is centred by the inner wall of the front end of the handle tube 47. Inserted in the front end of the turbine casing 53 is an annular disc 54 which is provided at its outer periphery with ducts 55 extending obliquely relatively to the axis. The annular disc 54 is held in the turbine casing by a front closure cap 56 having a tubular extension 57 which extends as far as the rear end of the front ball bearing 58. The outer race of the front ball bearing 58 is held centred in the nose part 48 of the handpiece. The front closure cap 56 is fixed to the turbine casing 53 by flanging-over the front end of the turbine casing at 59. Inserted in the rear end of the turbine casing 53 is the rear annular disc 60 which is provided at its outer periphery with ducts 61 disposed obliquely to the axial direction of the turbine shaft. At the rear, the rear annular disc 60 is followed by the rear closure cap 62, which is connected to the turbine casing 53 by the flanging-over of the free rear end of the said casing at 63. Arranged between the turbine rotor 50 and the rear end of the rear closure cap 62 is the rear ball bearing 64 whose inner race sits on the hollow turbine shaft 52.

The rear closure cap 62 also carries, in a recess of its rear end face, an annular rubber packing 65 whose rear end face bears with a sealing-type action against the front face of the spacer ring 66 which centres the front end of the centrally arranged air discharge pipe 67 with respect to the handle tube 47. The outer periphery of the spacer ring 66 is provided with axial slots 68, the significance of which will be described hereinafter.

The air discharge pipe 67 extends as far as the rear end of the handpiece. A closure cap 69 is screwed at 70 into the rear end of the handpiece. A further threaded cap 71, the bore of which serves to centre the rear end of the air discharge pipe 67, is screwed into a hole in the bottom of the closure cap 69. A rubber packing 72 is also provided between the closure cap 69 and the closure cap 71. The air supply stub pipe 74 is inserted at an inclination into the closure cap 69 through the side thereof to debouch into the chamber 73 in the said cap.

The air supplied through the stub pipe 74 passes through the annular chamber 73 and the annular chamber 75 between the air discharge pipe 67 and handle tube 47, through the axial slots 68 of the spacer ring 66, through radial holes 76 in the rear closure cap 62 and the inclined ducts 61 of the rear disc 60, into the turbine rotor 50.

The discharged air is guided through the inclined ducts 60 of the front annular disc 54 into the annular chamber 77 within the front closure cap and passes through radial apertures 78 in the hollow turbine shaft 52 through the hollow interior of the turbine shaft and the air discharge pipe 67 adjoining said turbine shaft at the rear thereof, and out into the atmosphere at the rear end of the handpiece.

Some of the turbine discharge air passes through the annular chamber 79 between the turbine shaft 52 and the tubular extension 57 of the front closure cap 56 through the front ball bearing 58 and through peripherally disposed nozzles 80 in the nose part of the handpiece to reach the tool which is inserted in the handpiece.

As in the form of embodiment according to FIGURES 1 to 5, a self-locking chuck 81 for the tool shank (not shown) is inserted in the front hollow end of the turbine

shaft 52. This chuck 81 which is made of elastic material is provided at its rear end with slots 82. The tongues situated between the slots 82 are slightly curved in the inward direction. When the tool shank is inserted in the chuck, the elastic tongues are pressed outwards, and the resulting spring action holds the tool shank fast.

A push rod 83 is arranged within the front end of the hollow turbine shaft 52 to permit removal of the tool shank from the chuck 81. The rear thickened end 84 of this push rod bears by means of the spring 85 on the ring 86 which is fixed in the hollow turbine shaft 52 somewhat in front of the apertures 78. The front end of the spring-loaded push rod 83 is guided in a bore in the turbine shaft 52 and extends approximately as far as the rear end of the tool shank (not shown) which is inserted in the chuck 81.

In order to eject the tool from the chuck 81, the push rod 83 is pressed forwardly in opposition to the action of the spring 85 by means of a hand rod which can be inserted through the hollow discharge pipe 67 from the rear end of the handpiece.

What is claimed is:

1. In an air driven dental drill including an elongated hollow handpiece provided at one end with a nose portion and having inlet and outlet means at the other end for motive air, shaft means including concentric rotor means at one end thereof and being provided with means at the other end to removably secure a dental bur therein, casing means to enclose said rotor, said casing including inlet and outlet means for motive air and also including air deflecting means within said casing at one end to direct air generally unidirectionally longitudinally into operative engagement with said rotor, anti-friction bearing means for said shaft, means to removably position said bearing means and said rotor casing within said handpiece adjacent said one end, said handpiece being comprised of at least two separable elements, one of said elements including conduit means for separable connection between the inlet and outlet means of said handpiece and the inlet and outlet means of said rotor casing, one of said elements being separable from the other to permit removal of said rotor casing shaft means and bearing means as a unit.

2. The invention as defined in claim 1, wherein said means to direct air into operative engagement with said rotor includes longitudinally extending passage means axially adjacent one end of said rotor in communication with the inlet means of the casing, said outlet means of the casing being in communication with the other end of the rotor, whereby motive fluid travels axially of the rotor.

3. The invention as defined in claim 1, wherein one of the separable elements of the handpiece comprises a nosepiece, and said means to removably position said bearing means and said rotor casing are both contained within said nosepiece, said rotor casing shaft means and bearing means being removable from said nosepiece as a unit.

4. The invention as defined in claim 1, wherein said means to direct air within the rotor casing includes two discs, positioned one at each end of the rotor, said discs being provided with a plurality of angularly disposed passages to induce an axial twist to said motive air.

5. The invention as defined in claim 1, wherein said rotor casing means is provided with a central opening at one end for motive air and said handpiece is provided with a concentrically arranged conduit extending between said opening and said other end of the handpiece, said conduit being joined to said rotor casing means at one end and separably connected to the handpiece at said other end of the handle to permit removal of said conduit, rotor casing means, shaft means and bearing means as a unit.

6. The invention as defined in claim 1, wherein said rotor casing is provided with a central opening at one

end for motive air and said handpiece is provided with a concentrically arranged conduit means extending between said opening and said other end of the handpiece, and coupling means is provided to establish communication between said conduit means and said opening, said coupling means including a conically formed element, said conduit means being detachably removable from said other end of the handpiece.

7. The invention as defined in claim 1, wherein said separable elements of the handpiece comprise a tubular handle portion and hollow nosepiece, said rotor casing being received and positioned within said handle portion, said rotor casing shaft means and bearing means being removable from said handle portion as a unit.

8. The invention as defined in claim 1, wherein said anti-friction bearing means includes two bearings, one disposed at the forward end of the shaft means, the other bearing being contained within the rotor casing means.

9. The invention as defined in claim 3, wherein said means to position said casing includes an annular seat provided on the inner wall of the nose portion, the forward end of said rotor casing being adapted to engage with said annular seat, the rear end of said casing being provided with an annularly projecting ring to engage with the inner surface of the nosepiece axially spaced from said seat, said casing having said inlet and outlet for motive air at opposite ends and being of less diameter than the interior of said nose portion to provide an annular passage for said air.

10. The invention as defined in claim 6, wherein said conduit means comprises one of the separable elements of the handpiece to permit removal of said rotor casing shaft means and bearing means as a unit.

11. The invention as defined in claim 6, wherein said conduit means includes an additional passage means in communication with the interior of the handpiece.

12. The invention as defined in claim 7, wherein said bearing means includes an anti-friction bearing at the forward end of the shaft means, and said nosepiece is provided with an annular seat to receive and removably position said anti-friction bearing.

13. The invention as defined in claim 8, wherein the bearing contained within the rotor casing is disposed at the rear end of the shaft means.

14. A dental handpiece comprising an elongated handle tube having a nose portion coaxial therewith at the front end thereof, an air turbine unit removably positioned within at least the front end portion of said handle tube and comprising in combination: a shaft rotatable coaxially within said nose portion, bearings carried by and spaced longitudinally of said shaft, means on the end of said shaft nearest the front end of said handpiece to receive a dental tool, and a turbine rotor fixed to said shaft adjacent the opposite end thereof and having impeller blades on the exterior thereof and extending substantially longitudinally along said rotor; and air conducting means in said handle tube extending generally longitudinally thereof from the rear end of said handle tube to the rearward ends of said impeller blades to direct air engageably with said blades generally unidirectionally longitudinally along said blades, to the front ends thereof, thereby to rotate said rotor, said handle tube and nose portion thereof having connected portions separable to permit removal of said air turbine unit as an assembly longitudinally therefrom.

15. The invention as defined in claim 14, wherein said air conducting means includes a disc-shaped member being positioned axially with respect to the rotor means, said member being provided with axially extending passages.

16. The invention as defined in claim 15, wherein said air conducting means includes conduit means disposed within the rear of the handle tube, and a cylindrical housing is provided to enclose said rotor and disc-shaped member, said housing having an opening adapted to separably connect with said conduit means.

17. The invention as defined in claim 16, wherein said means to separably connect said conduit means with said housing includes a flat resilient gasket member adapted to be interposed between the abutting ends of the conduit means and the opening in the rotor housing, and a radially extending member is connected at the one end of said conduit means to position said conduit means for said abutting engagement.

18. In an air driven dental handpiece including an elongated tubular member having a nose portion at one end and inlet and outlet connections for motive air at the other end, cylindrical rotor means including concentric hollow shaft means, bearing means for the shaft means to position said rotor means concentrically in said tubular member, said rotor means being provided with blade means positioned to be operative in response to motive air moving in an axial direction, conduit means disposed in said tubular member for communication between the rearward end of the hollow shaft and one of the motive air connections at the other end of the tubular member, said hollow shaft means being provided with a radial passage adjacent one end of the rotor means, passage means disposed at the other end of the rotor means in communication with the interior of the tubular member and the other of said motive air connections at the other end of the tubular member.

19. The invention as defined in claim 18, wherein said rotor means is enclosed within a cylindrical housing, said housing having a radially extending cap means closing one end thereof, said cap means including a concentric opening in alignment with said hollow shaft, said cap means also having a peripherally disposed opening in communication with the interior of the tubular member and the space surrounding the rotor blade means.

space surrounding the rotor blade means.

20. An air operated dental handpiece comprising, a hollow handle containing an air supply pipe, a nose portion having a bur receiving end and connected to said handle at its other end, a turbine casing containing an air rotor in said nose portion, a rotor shaft, an extension of said shaft extending to said bur receiving end, ball bearings rotatably supporting said shaft in said nose portion, said shaft having a bur receiving recess therein, a spring

mounted rod axially supported in said pipe extending through said handle and into said recess, said turbine casing being centered by means of a closure cap in the bore of the nose portion of the handpiece and the rear end thereof being centered by means of a closure cap on the front end of said pipe, said pipe being in turn centered by means of a ring on the rear end of the inner wall of the nose portion, said turbine casing and said nose portion defining an annular space therebetween for return of air discharged by said turbine.

21. In a fluid turbine driven dental drill, including a tubular handpiece, a turbine rotor including a hollow shaft, one end of said shaft being provided with frictional coupling means to removably receive a dental bur, said handpiece being provided with aligned openings at either end thereof, means to rotatably mount said shaft to position said coupling means adjacent one of the openings in the tubular handpiece, a first push rod slidably in said hollow shaft and movable in one direction to eject a bur, biasing means to urge said rod in the opposite direction, stop means to limit movement of the rod in said opposite direction, a second push rod slidably positioned within the handpiece in alignment with the first push rod, one end of the second push rod projecting outwardly from the other end of the handpiece, said second push rod being movable in one direction to actuate the first push rod, biasing means to urge the second push rod in the opposite direction, and stop means to limit movement of the second push rod in said opposite direction.
